REFRIGERATION

William H. Kitto, Canton, Ohio, assignor to The
Hoover Company, North Canton, Ohio

Application September 16, 1939, Serial No. 295,223

14 Claims. (Cl. 62—119.5)

This invention relates to the art of refrigeration and more particularly to absorption refrigerating systems of the three-fluid type and evaporators for use therein.

In the co-pending application of William H. Kitto and Curtis C. Coons, Serial No. 220,189, filed July 20, 1938, there is disclosed an absorption refrigerating system of the three-fluid type including an evaporator in which the liquid refrigerant is supplied to the bottom portion of the evaporator and is propelled upwardly therethrough by a propelled stream of inert gas into which the liquid evaporates. This evaporator is satisfactory but it cannot conveniently be constructed over 12" in height without necessitating a cumbersomely large fan for circulating the inert gas or without producing an excessive pressure drop between the gas inlet and outlet portions of the evaporator.

Accordingly, it is a principal object of the present invention to provide an evaporator adapted for use in three-fluid absorption refrigerating systems in which the inert gas propels the liquid refrigerant through only a portion of the evaporator whereby the evaporator may be made of relatively great height without necessitating an increase in the size of the circulating fan or an objectionably large pressure drop within the evaporator.

It is another object of the invention to provide an evaporator of the type above referred to in which the evaporator includes a box-cooling section connected between a pair of ice-freezing or low temperature refrigerating sections.

It is a further object of the invention to produce an evaporator of the type above referred to in which the liquid refrigerant is supplied intermediate the top and bottom portions thereof and divides into two streams one of which flows downwardly from its point of supply from the condenser and the other of which travels first upwardly through one portion of the evaporator and then downwardly through another portion thereof.

It is a further object of the invention to provide an evaporator of the type above referred to which will have relatively stable, constant, and equal temperature distribution throughout the various portions thereof.

Other objects and advantages of the invention will become apparent as the description proceeds when taken in connection with the accompanying drawing, in which:

There is illustrated diagrammatically an absorption refrigerating system of the three-fluid

type embodying an evaporator which is illustrated on an enlarged scale and in perspective.

The refrigerating system comprises a boiler B, an analyzer D, an air-cooled rectifier R, a tubular air-cooled condenser C, an evaporator E, a gas heat exchanger G, a tubular air-cooled absorber A, a liquid heat exchanger L, a solution reservoir S, and a circulating fan F which is driven by an electrical motor M. These elements 10 are suitably connected by various conduits to form a plurality of gas and liquid circuits constituting a complete refrigerating system to which reference will be made in more detail hereinafter.

15 The above described refrigerating system will be charged with a suitable refrigerant, such as ammonia, a suitable absorbent, such as water, and an inert pressure equalizing medium, preferably a dense inert gas like nitrogen.

20 The boiler B may be heated in any suitable or desired manner as by an electrical cartridge heater or a combustible fuel burner.

The circulating motor and the heater for the boiler may be controlled in any suitable manner.

25 A preferred control mechanism is disclosed and claimed in the co-pending application of Curtis C. Coons, Serial No. 148,424, filed June 16, 1937.

Though the invention is concerned primarily with the evaporator construction, it is necessary 30 to describe the system in considerable detail in order to achieve an understanding of the evaporator construction and operation. Therefore, the system will be described first in order to provide proper background for a description of 35 the evaporator.

The application of heat to the boiler B generates refrigerant vapor from the strong solution therein contained. The vapor so liberated passes upwardly through the analyzer D in counterflow relationship with the strong solution flowing downwardly therethrough. The heat of condensation of absorption solution vapor liberated in the boiler serves to generate further refrigerant vapor in the analyzer. The refrigerant vapor is conveyed from the analyzer to the upper portion of the condenser C by the conduit 11 which includes the rectifier R. The rectifier R causes condensation of vapor of absorption solution which passes through the analyzer D.

40 50 The weak solution formed in the boiler by the generation of refrigerant vapor is conveyed therefrom to the solution reservoir S by means of the conduit 12, the outer path of the liquid heat exchanger L, and the finned air-cooled solution pre-cooler 13. The solution collecting in

the solution reservoir S is enroute to the upper portion of the absorber A. However, it is apparent that the upper portion of the absorber is at an elevation considerably above the elevation of the boiler analyzer system wherefore some means must be provided to elevate the absorption solution thereinto.

For this purpose, a gas lift pump 15 is connected between the bottom portion of the solution reservoir S and the suction conduit 16 of the circulating fan F which opens into the top portion of the absorber A. A small gas bleed conduit 17 is connected between the discharge conduit 18 of the circulating fan and the gas lift pump conduit 15 below the liquid level normally prevailing in the boiler-analyzer system, wherefore the absorption solution is elevated into the absorber by gas lift action.

The absorption solution flows downwardly through the absorber A by gravity counter to the rich mixture of pressure equalizing medium and refrigerant vapor flowing upwardly therethrough. The refrigerant vapor content of the mixture is absorbed in the solution and the heat of absorption is rejected to cooling air flowing over the exterior walls of the absorber vessel and the fins attached thereto. The strong solution formed in the absorber is returned therefrom to the upper portion of the analyzer D by way of conduit 19, the inner path of the liquid heat exchanger L, and the conduit 20.

A small vent conduit 21 is connected between the upper portion of the solution reservoir S and the suction conduit 16 in order that the suction pressure of the fan may prevail in the reservoir S wherefore the maximum possible pressure differential available in the system is utilized to operate the gas lift pump 15.

The lean pressure equalizing medium formed in the absorber A is conveyed therefrom by conduit 16 into the suction side of the circulating fan F in which it is placed under pressure. The pressure equalizing medium placed under pressure of the fan F is conveyed therefrom to the bottom portion of the evaporator E by way of the conduit 18, the outer path of the gas heat exchanger G and the conduit 25.

It is not necessary to describe the exact construction and operation of the evaporator at this time. For the present purpose it is sufficient to note that the inert gas passes through the evaporator in contact with the liquid refrigerant which evaporates into the inert gas stream to produce refrigeration. The rich gas formed in the evaporator is removed therefrom through the conduit 23 into the inner path of the gas heat exchanger G from which it is returned by way of the conduit 24 to the bottom portion of the absorber A. The inert gas passes upwardly through the absorber A in the manner heretofore described. The evaporator E is provided with a suitable drain conduit 28 which connects to the strong solution return conduit 19.

The refrigerant vapor is liquefied in the condenser and is discharged therefrom into the evaporator through a conduit 22 which includes a U-shaped sealing portion. The liquid refrigerant supply conduit 22 is provided with a small vent conduit 29 connected between the condenser side of the liquid seal in the conduit 22 and the rich gas side of the gas heat exchanger.

Beginning with the gas inlet conduit 25 the evaporator E comprises a large diameter conduit section including a horizontal bottom U-shaped coil 30 which is connected by a riser conduit 31

to a parallel superposed U-shaped coil 33 which terminates in a riser conduit 34.

The riser 34 telescopically receives a portion of a riser conduit 35 of smaller diameter which connects to a horizontal superposed U-shaped conduit 37 parallel to the U-shaped conduits 30 and 33. The coil section 31 terminates in a riser conduit 38 which connects to a top box-cooling U-shaped coil 39. The leg of the U-shaped coil 39 not connected to the riser 38 terminates in a riser conduit 40 which connects to another U-shaped horizontal coil section 41 lying in the plane of the coil section 37. Similarly, coil sections 43 and 45 are U-shaped and lie in the planes of the coil sections 33 and 30, respectively. However, all the evaporator conduit elements having reference characters higher than 34 are small diameter conduits. The coil section 45 terminates in the rich gas discharge conduit 23. Riser conduits 42 and 44 correspond to the riser conduits 35 and 31, respectively. Therefore, it will be seen that the evaporator comprises a plurality of pairs of U-shaped coil sections which are superposed and lie in parallel horizontal planes and which are serially connected at their top portions by the U-shaped box-cooling conduit 39 and its associated riser conduits.

The gas outlet conduit 23 adjacent its point of connection with the coil section 45 is provided with a small dam 50. A U-shaped conduit 51 connects the gas outlet portion of the coil section 45 ahead of the dam 50 to the gas inlet portion of the coil section 30 inwardly of the point of connection between the drain conduit 28 and the gas inlet conduit 25.

The operation of the invention is as follows: The liquid refrigerant formed in the condenser is conveyed to the riser conduit 35 by means of the conduit 22, wherein it meets a high velocity stream of the inert gas. The diameter of the conduit sections having reference characters of 35 and above are purposely made small, for example, $\frac{1}{2}$ " inside diameter for use with a fan developing approximately $4\frac{1}{2}$ " of water pressure differential, so as to insure that the inert gas will flow therethrough with a velocity sufficient to sweep or drag the liquid refrigerant through the conduit under the impetus of the gas stream. However, the conduit sections 30 to 34, inclusive, are made of a relatively large diameter, for example 1" inside diameter, so that the gas will flow therethrough at a slow rate and the liquid will counterflow to the gas stream under the influence of gravity.

Liquid supplied to the conduit section 35 divides into two streams one of which discharges into the coil section 33 and the other of which is elevated into the coil section 37. The construction and operation of the conduit sections 34 and 35 is disclosed and claimed in the co-pending application of Curtis C. Coons and William H. Kitto, Serial No. 220,187, filed July 20, 1938, and will not be described in detail herein. The refrigerant liquid is propelled through the coil section 37 by the inert gas stream and is thereafter elevated through the riser conduit 38 into the finned box-cooling conduit 39 through which it is also propelled by the inert gas. After passing through the finned box-cooling conduit 39, the liquid refrigerant is propelled downwardly through the riser conduit 40, coil section 41, riser 42, coil section 43, riser 44, and coil section 45 to the drain conduit 51 which carries any unevaporated liquid into the inlet portion of the coil section 30 through which it flows to the drain 28.

From this it will be seen that the pressure equalizing medium is required to elevate the inert gas through only a portion of the total height of the evaporator and, further, it is not required to propel the refrigerant except through the coil sections 37 and 39 on the upflow side and through the horizontal coil sections 41, 43 and 45 on the downflow side. The inert gas actually elevates the refrigerant only through the risers 35 and 38.

In refrigerating systems of the type above described the inert gas is circulated by a very small fan which develops a pressure differential on the order of $4\frac{1}{2}$ " of water. Using nitrogen, a fan of approximately 4" in diameter is satisfactory for this purpose and will fit conveniently within the cooling air flue normally provided in the rear portion of refrigerator cabinets to provide space for the condenser and absorber, etc. and also to provide for cooling of these elements. However, if the resistance of the inert gas circuit should be greater than $4\frac{1}{2}$ " of water, it will be necessary to increase the size of the fan which will necessitate either an increase in the depth of the cooling air flue which greatly increases the cost of the apparatus and greatly decreases space efficiency thereof or it will be necessary to decrease the resistance of the absorber and gas heat exchanger which is highly undesirable.

With systems of the type above referred to approximately 3" of water is the maximum resistance allowable in the evaporator. This pressure differential is sufficient if the evaporator is not to be over 12" in height and does not have extremely long and complex coils. However, with some types of the domestic refrigerators it is desirable to provide an evaporator exceeding 12" in height and also having a very wide spread coil construction. The instant invention provides an evaporator which will meet these requirements without exceeding the allowable gas flow resistance.

The major portion of the resistance to gas flow in evaporators of this type occurs in the riser conduits thereof on the lifting side at which point the inert gas is continuously blowing its way through a body of refrigerant collected in the riser. Of course, some resistance to gas flow is offered by substantially horizontal conduit sections in which the liquid refrigerant is traveling in the form of a stream under the frictional drag of the gas stream flowing theracross but this resistance is not large.

With the construction illustrated it will be noted that the inert gas is actually elevating the liquid only through about one-half of the total evaporator height. Through one-half the evaporator height the inert gas is travelling at a rather slow rate counter to a gravity propelled stream of liquid and through one-half of the evaporator the inert gas is travelling with a generally downwardly flowing stream of liquid which will not offer a large resistance to the flow of the inert gas. Therefore, the evaporator may have an extensive height without offering an excessive resistance to gas flow and without imposing a burdensome liquid refrigerant lifting load on the circulating fan.

The apparatus above described will be housed in a suitable cabinet with the evaporator in the top portion of an insulated storage chamber and the balance of the apparatus suitably positioned in a rear air duct and bottom mechanism chamber. Due to the fact that the liquid inlet to the evaporator is well below the top thereof, the con-

denser may have a large vertical dimension without extending above the top wall of the cabinet.

The evaporator will be encased in a suitable chamber including ice tray supporting shelves resting upon the horizontal coil sections.

The gas inlet and outlet connections to the evaporator lie in the lowest plane thereof which facilitates connections to the gas heat exchanger and prevents interference between the condenser, refrigerant conduit and inert gas conduits. This arrangement permits the inert gas connections to the evaporator to be disposed in heat exchange relationship and to lie in a common opening in the panel element customarily provided in the rear wall of domestic refrigerators to allow the evaporator to be inserted into the storage chamber after it is welded into the system.

The instant invention furthermore provides a very efficient arrangement of the coil construction in that the coils may be widely separated and each of the individual U-shaped coil sections may be arranged so as to provide freezing for one or more ice trays. Moreover, if desired, the coils may be spread widely apart whereby to provide two widely spaced ice-freezing sections which are joined by an upper intermediate box-cooling coil. Such an arrangement, for example, would be very advantageous in a refrigerator normally called upon to refrigerate extremely tall bottles or like receptacles. In this event the right and left hand groups of coils would be enclosed in separate cabinets and spaced an appreciable distance apart which would thus provide a central duct for cooling the air within the refrigerating compartment and for refrigerating tall receptacles. With such an arrangement the finned air-cooling coil 39 would be centrally located with respect to the cabinet and between the separated coil sections; also it would not be necessary to elevate the coil 39 above the level of the coils 37 and 41, thus replacing risers 38 and 40 with simple horizontal return bend conduits.

The present invention is highly efficient and useful because of the wide scope of its design without materially altering the gas flow resistance therethrough and without imposing an unusual load upon the circulating fan. Though the evaporator has been shown as being provided with counterflow sections at two elevations, this is by no means the only possible arrangement. For example, one or three or more such sections could equally well be provided if desired.

Though the invention has been illustrated and described in detail, it is not to be construed as being limited to the precise construction and arrangement shown, as various changes may be made in the proportion, arrangement and construction of parts without departing from the spirit of the invention or the scope of the appended claims.

I claim:

1. Absorption refrigerating apparatus comprising an inert gas circuit including an evaporator and an absorber, a solution circuit including a boiler and said absorber, means for propelling inert gas through said inert gas circuit, means for liquefying refrigerant vapor generated in said boiler, said evaporator comprising two freezing sections serially connected by a finned air cooling section, one of said sections comprising a lower portion of large cross-sectional area connected to receive inert gas at its bottom and an upper portion of small cross-sectional area such that inert gas flowing therethrough will propel refrigerant upwardly, the other of

said sections being connected to discharge inert gas from its bottom portion, and means for supplying liquid refrigerant to an intermediate portion of said one section whereby a portion of the liquid flows downwardly through said portion of large cross-sectional area and the balance of the liquid is circulated through the remainder of the evaporator by the inert gas.

2. Absorption refrigerating apparatus comprising an inert gas circuit including an evaporator and an absorber, a solution circuit including a boiler and said absorber, means for propelling inert gas through said inert gas circuit, means for liquefying refrigerant vapor generated in said boiler, said evaporator comprising a spaced pair of sections each comprising serially connected vertically spaced U-shaped conduit elements, a U-shaped finned box-cooling conduit connected to the top portion of each of said sections, means for connecting said evaporator in said inert gas circuit to cause gas to flow up one side and down the other side thereof, and means for supplying refrigerant to said evaporator.

3. Refrigerating apparatus comprising an evaporator consisting of a plurality of sets of coplanar coils, the coils in each set of coplanar coils being serially connected to corresponding coils in another such set to form groups of serially connected coils, certain of the coils in one of said groups having a larger cross-sectional area than the other coils in said group, means for supplying liquid refrigerant to said one group of coils adjacent the junction between coils of large and small cross-sectional area, and means for propelling a dense inert gas through said coils, the arrangement being such that the liquid is circulated through the coils of small cross-sectional area by the frictional drag of the inert gas.

4. Refrigerating apparatus comprising an evaporator consisting of a plurality of sets of coplanar coils, the coils in each set of coplanar coils being serially connected to corresponding coils in another such set to form groups of serially connected coils, means serially connecting each group of coils, means for supplying liquid refrigerant to said coils, means for propelling an inert gas through said coils to circulate the refrigerant therethrough as it is evaporating, means for draining unevaporated matter from the gas outlet portion of one of said groups of coils into the gas inlet portion of the other of said groups of coils, and means for removing unevaporated material from said other group of coils.

5. Absorption refrigerating apparatus comprising an absorption solution circuit including a generator and an absorber, an inert gas circuit including said absorber and an evaporator, means for liquefying refrigerant vapor produced in said generator and for supplying the liquid refrigerant to said evaporator, said evaporator comprising a pair of vertically extending coil sections serially connected at their upper ends by a space cooling element, the gas inlet and outlet connections to said evaporator being coplanar and adjacent the bottom portion thereof.

6. Absorption refrigerating apparatus comprising an absorption solution circuit including a generator and an absorber, an inert gas circuit including said absorber and an evaporator, said evaporator comprising a pair of laterally spaced freezing sections serially connected by a space cooling element at their upper ends, one of said freezing sections comprising a lower portion of large cross-sectional area and an upper portion

of small cross-sectional area, means for liquefying refrigerant vapor produced in said generator and for supplying the liquid to said evaporator adjacent the junction of said portions of large and small cross-sectional area, and means in said inert gas circuit for propelling inert gas upwardly through said portion of small cross-sectional area with a velocity sufficient to propel the refrigerant liquid therethrough as it is evaporating.

7. That improvement in refrigerating systems utilizing a refrigerant, an absorbent for the refrigerant and a pressure equalizing medium inert with respect to the refrigerant and the absorbent which includes the steps of propelling the pressure equalizing medium upwardly through one section of an evaporating zone and downwardly through another section thereof, supplying liquid refrigerant to an area of the evaporating zone in which the gas flows upwardly, flowing the liquid refrigerant through a portion of the evaporating zone by gravity counter to the upwardly flowing gas, and propelling the liquid refrigerant through another portion of the evaporating zone under the frictional drag of the inert gas.

8. That improvement in refrigerating systems utilizing a refrigerant, an absorbent for the refrigerant and a pressure equalizing medium inert with respect to the refrigerant and the absorbent which includes the steps of propelling the pressure equalizing medium upwardly through one section of an evaporating zone and downwardly through another section thereof, supplying liquid refrigerant to an area of the evaporating zone in which the gas flows upwardly, flowing the liquid refrigerant through a portion of the evaporating zone by gravity counter to the upwardly flowing gas, propelling the liquid refrigerant upwardly through another portion of the evaporating zone under the frictional drag of the inert gas, and flowing the liquid refrigerant in the same direction as the gas stream in another portion of the evaporating zone.

9. Absorption refrigerating apparatus comprising an inert gas circuit including an upstanding evaporator and an absorber, an absorption solution circuit including a boiler and said absorber, said evaporator being connected to said inert gas circuit in such fashion that inert gas flows upwardly in one side thereof and downwardly in the other side thereof, means for liquefying refrigerant vapor produced in said boiler and for supplying the liquid to said evaporator at a level intermediate the top and bottom portions thereof on the gas upflow side thereof, and an inert gas circulator in said inert gas circuit for circulating the inert gas therethrough with sufficient force to circulate the liquid refrigerant upwardly through only that portion of the evaporator above the liquid refrigerant inlet thereto.

10. In an absorption refrigerating apparatus of the three-fluid type an evaporator comprising a pair of upstanding sections serially connected at their upper portions, an inert gas inlet connected to the bottom of one of said sections and an inert gas outlet connected to the bottom of the other of said sections, means for supplying liquid refrigerant to the gas upflow section, and means for propelling the inert gas through at least a portion of the gas upflow section with a velocity sufficient to sweep or drag the refrigerant liquid upwardly therethrough whereby liquid refrigerant flows upwardly and then downwardly

in parallel flow relationship through at least part of said evaporator.

11. Absorption refrigerating apparatus comprising an inert gas circuit including an evaporator and an absorber, a solution circuit including a boiler and said absorber, means for liquefying refrigerant vapor generated in said boiler, said evaporator being constructed of a conduit having inert gas inlet and inert gas outlet portions, said conduit extending upwardly from said inert gas inlet portion and then downwardly to said inert gas outlet portion, means for conducting liquid refrigerant from said liquefying means to the said upwardly extending part of said evaporator, and means in said inert gas circuit for propelling inert gas through at least a part of the upwardly extending portion of said evaporator with a velocity sufficient to propel liquid refrigerant upwardly therethrough by the frictional drag of the inert gas whereby refrigerant liquid flows upwardly through a part of said conduit under the propulsion of the inert gas and flows downwardly through another part of said conduit in contact with the inert gas.

12. Absorption refrigerating apparatus comprising an inert gas circuit including an evaporator and an absorber, a solution circuit including a boiler and said absorber, means for liquefying refrigerant vapor generated in said boiler, said evaporator being constructed of a conduit having inert gas inlet and inert gas outlet portions, said conduit extending upwardly from said inert gas inlet portion and then downwardly to said inert gas outlet portion, means for conducting liquid refrigerant from said liquefying means to an intermediate level of the said upwardly extending

part of said evaporator, and means in said inert gas circuit for propelling inert gas through at least a part of the upwardly extending portion of said evaporator with a velocity sufficient to propel liquid refrigerant upwardly therethrough by the frictional drag of the inert gas whereby refrigerant liquid flows upwardly through a part of said conduit under the propulsion of the inert gas and flows downwardly through another part of said conduit in contact with the inert gas.

13. An evaporator construction comprising a first upstanding chilling coil section, a gas supply connection to said first chilling coil section adjacent the bottom thereof, a second upstanding chilling coil section positioned laterally of said first chilling coil section, a gas outlet connection to said second chilling coil section adjacent the bottom thereof, a space cooling coil section serially connecting the upper portions of said chilling coil sections, and a liquid refrigerant supply connection to said first chilling coil section.

14. An evaporator construction comprising a first upstanding chilling coil section, a gas supply connection to said first chilling coil section adjacent the bottom thereof, a second upstanding chilling coil section positioned laterally of said first chilling coil section, a gas outlet connection to said second chilling coil section adjacent the bottom thereof, a finned space cooling coil section serially connecting the upper portions of said laterally positioned chilling coil sections and positioned therebetween, and a liquid refrigerant supply connection to said first chilling coil section.

WILLIAM H. KITTO.
